R. TAUB

COLLAPSIBLE TUBE PASTE FILLER AND CLOSER

Original Filed Feb. 5, 1925

UNITED STATES PATENT OFFICE.

RAPHAEL TAUB, OF NEWARK, NEW JERSEY.

COLLAPSIBLE-TUBE PASTE FILLER AND CLOSER.

Application filed February 5, 1925, Serial No. 6,914. Renewed October 8, 1927.

This invention relates to apparatus for filling commercial collapsible tubes or containers with such material as ointments, salves and all kinds of pastes such as are supplied in tubes of the specified character.

It is primarily intended for the pharmacist in dispensing ointments, salves and the like from physicians' prescriptions calling for small quantities of paste and is capable 10 of practical operation on any desired quantity of pasty substance in an easy and rapid manner, without loss or waste.

Another aim is to provide means whereby different sizes of tubes can be filled with the 15 apparatus by changing the nozzle to suit.

These several aims and objects are attained by the novel construction and arrangement of parts hereinafter described and shown in the accompanying drawing, 20 forming a material part of this disclosure, and in which:

Figure 1 is a partial side elevational, partial longitudinal sectional view of a tube filling apparatus made in accordance with 25 the invention.

Figure 2 is a transverse sectional view taken on line 2—2 of Figure 1.

Figure 3 is an enlarged fragmentary view of the substance reservoir and its unsheathing sleeve. 30

Figure 4 is a transverse sectional view taken on line 4—4 of Figure 3.

Figure 5 is a similar view taken on line 5—5 of Figure 3.

Figure 6 is a transverse sectional view, similar to Figure 4 but showing the reservoir in an open position.

Figure 7 is a fragmentary side elevational view of the apparatus as used in shaping 40 and folding the tube after filling.

Referring more in detail to the drawing, the numeral 10 designates the base of the apparatus which may be fastened by screws 11 to any suitable supporting surface.

45 A body 12 is supported on a stand 13 rising from the base 10, this body being essentially horizontally disposed and containing a longitudinal bore 14 reduced at the front end, as at 15, and thereafter counterbored 50 from the front as at 16.

A bracket 17 provided with a flanged base is secured on the rear end of the body, this bracket being bored to slidably receive a plunger rod 18 of considerable length, 55 which also slides in the reduced bore 15 of

the body, and is provided at its outer extending end with a hand actuating knob 19.

The rod 18 contains a slot or keyway 20 midway in its length, in which is engaged the point of a screw 21, set in the bracket 60 17, to act as a key preventing rotation of the plunger rod.

At the extreme front end of the rod is secured a piston or plunger 22, held by screw-threads or other preferred means, 65 which may fit the counterbore 16 to seat therein and is interchangeable with others of different diameters.

Loosely mounted on the rod 18, within the bore 14 of the body, is a slidable collar 70 23 pressed normally outward against the shouldered front end of the bore by a compression spring 24 coiled about the rod and abutting the collar.

A recess 25, leading from the bore of the 75 bracket 17, through its entire length permits a pin 26 to pass through the bracket, engage the collar 23 and compress the spring when the rod is pressed forward to cause such action.

A socket 27 is held on the front of the body by screws or other removable means, this socket being provided with a thumb screw 28 intersecting the bore 29 of the socket, which is in register with the bore 14 80 of the body.

A cylindrical reservoir 30, composed of two equal longitudinal sections, connected near one end by a hinge 31, is fitted to engage in the socket 27 and may be clamped 85 therein by the screw 28, one end of the hinge abutting the outer end of the socket, at which time the inner end of the reservoir makes contact with the face of the body, it being understood that the piston 16 is neatly 90 fitted to the opening in the reservoir.

Any ointment, salve or pasty substance 95 32 may be deposited readily in the reservoir when the walls are opened and separated, as shown in Figure 6, which upon closing are 100 inserted in the socket and secured by the screw 28.

A tubular sleeve or sheath 33 is passed over the reservoir, confining it in closed position, preventing separation of the reservoir walls this sleeve extending circumjacent the reservoir from the hinge 31 to the outer end, and as shown in Figure 1, the outer diameter of the sleeve is such as to neatly 105 fit within the open rear end of the collaps- 110

ible tube 34 to be filled, which is drawn its full length over the sleeve and held thereover by the fingers of an operator, it being understood that the tube is provided with a cap or closure 34' to prevent extrusion of the entered substance.

In case of using tubes of larger or smaller diameter, the socket 27 is replaced with another of suitable size, as is the reservoir 30 and sheath 33, together with a corresponding piston 22, to suit the diameter of the tube to be filled.

The upper portion of the body 12 is shaped to present a bevelled anvil surface 35 and at the front thereof is a sharply angled surface 36.

A hand lever 37 having equally angularly flanged elements 38 fitting the sides of the body, is pivoted on the screws 39, these 20 flanges having arms 40 carrying a cross-bar 41, the upper edge of which is sharply bevelled.

After filling the tube it is placed on the anvil 35 and the lever 37 pressed thereover, 25 squeezing the open end of the tube into the shape of a wedge having a flattened edge extension 42.

Thereafter the flattened extension 42 is placed between the angular surface 36 and 30 bevelled portion of the bar 41, at that time presenting an open space receptive of the same, and upon depression of the lever 37, together with obvious manipulations of the tube, its flattened extension will be folded 35 and securely crimped. As many folds as may be desired can thus be made.

Although the foregoing is descriptive of the improvements in considerable detail, many minor changes may be made without 40 departing from the scope of the invention in its broadest aspect.

Having thus described my invention, including the manner of its operation and use, what I claim as new and desire to secure by 45 Letters Patent is:—

1. A tube filling apparatus comprising a stand having a raised elongated body containing a longitudinal bore, a bracket at one end thereof, a plunger rod movable in 50 the bore of said body and extending through the bracket, said rod having an operating knob at its outer end, and a plunger at the other end, means in said body to elastically limit the stroke of said plunger, a socket on 55 the opposite end of the body, a hollow cylinder split lengthwise to present two equal sections connected by a hinge, means to secure said cylinder in said socket, and a sleeve slidably engaged over said cylinder,

said plunger being movable in the cylinder 60 to press material contained therein into a tube engaged over said sleeve.

2. A tube filling apparatus comprising a frame having a guide bore, a plunger rod 65 slideable therein, means to prevent rotation of said rod, a compression spring encircling said rod within a portion of the bore, a collar loose upon said rod in contact with said spring, a pin in said rod adapted to engage said collar at a definite point in the stroke 70 of said rod, a plunger carried at the inner end of the rod, and a tube receiving bracket engaged on said frame in register with said plunger.

3. In a tube filling apparatus, the combination with a stand, and a manually operable plunger rod guided therein, of a bracket removably engaged on said stand in register with the plunger, a tubular reservoir composed of two equal sections hinged 80 connected at one of their longitudinal edges, means for securing said reservoir in said bracket, a cylindrical sleeve enclosing said reservoir over which a tube to be filled is drawn, and means to secure the sleeve 85 when in position for use.

4. In a tube filling apparatus, the combination with a stand, and a manually operable plunger rod guided therein, said rod having a key-way and a bracket having a 90 slot on said stand through which the rod operates, of a key in said bracket engaging the key-way, a pin in said rod to pass through the slot in the bracket, a collar loose on said rod against which said pin 95 makes contact near the termination of its stroke, a spring in said stand to urge said collar outwardly against the bracket, a plunger on the inner end of said rod, a removable reservoir held in register with the 100 path of said plunger, and a cylindrical sleeve enveloping said reservoir.

5. In a tube filling apparatus, the combination with a stand, and a manually operable plunger rod guided therein, of 105 brackets on each end of said stand, guiding means for said rod carried by one of said brackets, a split cylindrical container for material and a tube engaging means carried by the other bracket, said container carrying bracket being interchangeable, and a piston 110 removably engaged on said rod to register with the tube filling means and pass through said container.

In witness whereof I have affixed my 115 signature.

RAPHAEL TAUB.
